CLAIM

The ornamental design for a roof rack for vehicles, as shown and described.

DESCRIPTION

FIG. 1 is a front perspective view of a “roof rack for vehicles”, showing my new design, shown without lights for clarity of illustration;

FIG. 2 is an enlarged side elevational view, the other side being a mirror image thereof, shown without lights for clarity of illustration;

FIG. 3 is an enlarged bottom plan view thereof, shown without lights for clarity of illustration;

FIG. 4 is an enlarged front end view thereof, shown without lights for clarity of illustration;

FIG. 5 is an enlarged rear end view thereof, shown without lights for clarity of illustration;

FIG. 6 is an enlarged side elevational view thereof with lights added;

FIG. 7 is an enlarged front end view thereof with lights added; and,

FIG. 8 is an enlarged rear end view thereof with lights added.
